Primary Examiner — Kendra Leslie Hamilton*Assistant Examiner* — Elizabeth S Struble(74) *Attorney, Agent, or Firm* — NKL LAW; Jae Youn Kim(57) **CLAIM**

We claim the ornamental design for a specimen collection equipment, as shown and described.

DESCRIPTION

FIG. 1 is a perspective view of a specimen collection equipment, showing our new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof;
 FIG. 8 is a sectional view of taken along line 8-8 in FIG. 2;
 FIG. 9 is an enlarged view of portion 9 of FIG. 8;
 FIG. 10 is an enlarged view of portion 10 of FIG. 2; and,
 FIG. 11 is an enlarged view of portion 11 of FIG. 1.
